UNITED STATES PATENT OFFICE.

JOHN F. McGINNITEY AND ROSS C. COX, OF ST. JOSEPH, MISSOURI

PARALLELOGRAM CUTTING-MACHINE.

1,279,892.

Specification of Letters Patent. Patented Sept. 24, 1918.

Application filed February 27, 1917. Serial No. 151,325.

To all whom it may concern:

Be it known that we, JOHN F. McGINNITEY and Ross C. Cox, citizens of the United States, residing at St. Joseph, in the county 5 of Buchanan and State of Missouri, have invented certain useful Improvements in Parallelogram Cutting-Machines, of which the following is a specification, reference being had therein to the accompanying 10 drawing.

The invention relates to a cutting machine, and more particularly to the class of butter cutters.

The primary object of the invention is 15 the provision of a machine or device of this character wherein molded butter or other like substance can be cut into block form so as to segregate the blocks from the molded mass, and these blocks will be of uniform sizes with respect to each other so that 20 the substance can be served, as the block forms will have artistic shape to appeal to a customer or purchaser.

Another object of the invention is the 25 provision of a cutter of this character wherein the construction thereof is novel in form so that the cutting wires can be strung and tensioned for the successful operation of the machine or device.

30 A further object of the invention is the provision of a machine or device of this character wherein the material or substance placed therein will be cut into a number of cubes or squares of uniform size and bulk, 35 and said machine or device is designed particularly for the cutting of butter, potatoes, veal loaf, mush or the like.

A still further object of the invention is 40 the provision of a machine or device of this character which is extremely simple in construction, thoroughly reliable and efficient in its operation, strong, durable and inexpensive in manufacture.

45 Other objects will be in part obvious and in part hereinafter set forth.

The invention accordingly consists in the 50 features of construction, combination of elements and arrangement of parts which will be exemplified in construction hereinafter set forth, and the scope of the application of which will be indicated in the appended claims.

In the accompanying drawings:

55 Figure 1 is a side elevation of a machine or device constructed in accordance with the invention;

Fig. 2 is a top plan view thereof;

Fig. 3 is a bottom plan view;

Fig. 4 is a vertical transverse sectional view;

Fig. 5 is a vertical longitudinal sectional view;

Fig. 6 is a plan view of the frame with the adjunct parts of the device or machine separated therefrom.

Similar reference characters indicate corresponding parts throughout the several views of the drawings.

Referring to the drawings in detail, the machine or device comprises a box-like body 10, preferably made from metal molded or cast, although it may be made from any other suitable material and constructed in any other desirable manner, while marginally of this body, at the bottom thereof, is a 15 cutter frame including longitudinal substantially channel-shaped spaced parallel side rails 11 and cross end rails 12 which are similar to the side rails and are integral with the latter or fastened thereto in any 20 suitable manner. It is preferable, however, in manufacture to cast the frame, although it may be otherwise made. The outer surface of the intermediate portions of the side and end rails constitute the inner surface of the frame while the upper and lower portions of the rail extend outwardly and laterally of the inner surface of the intermediate portions for a purpose that will 25 presently appear. The side rails 11 extend 30 a distance beyond the end rails 12 and thus serve as handles in the use of the machine or device.

Bridging the frame both longitudinally 35 thereof and transversely of the same are spaced parallel longitudinal cutting wires 13 and transverse cutting wires 14, respectively, the rails 11 and 12 being channeled or grooved to form counterseats for the 40 wires 13 and 14, which are engaged therein.

Mounted between the upper and lower 45 portions of the side and end rails 11 and 12 are tension bars 16, while rising medially from the lower portions of said rails are guide pins 17 which pass through the tension bars 16, the latter being fitted with adjusting screws 18 near their ends, and these screws operate through the upper portions of the rails 11 and 12 and work against the 50 rails 11 and 12 for a purpose presently described.

Mounted in the tension bars 16 at inter-

vals thereof are headed anchoring lugs 19, about which are trained the looped ends 20 of the cutting wires 13 and 14, while the terminals of these wires are fastened to 5 certain of the said lugs 19, and on the adjustment of the bars 16 the cutting wires 13 and 14 will be properly tensioned for rendering the stretches thereof taut, as will be obvious.

- 10 Working within the body 10 is a presser plate 21 which is formed with a medial stem 22 having a cross handle 23, and this plate acts upon the bulk of material placed within the body 10 so that on pressing thereupon 15 the material will be worked through the open bottom end of said body 10 and the wires 13 and 14 will sever the mass of material into block or cube form, thereby segregating the blocks or cubes from each other.
- 20 The plate 21 in its working face is formed with longitudinal and transverse grooves 24 and 25, respectively, which register with the stretches of the cutting wires 13 and 14 so as to receive the same on the completed 25 movement of the plate 21 in the operation of the cutting device or machine so as to assure on the completed movement the complete severance of the blocks or cubes from the bulk material on deliverance thereof 30 from the device or machine.

It is of course to be understood that while there are shown pairs of the tension bars 16, if it is desirable, a single bar can be used at one side and one end of the body, while 35 the other side and end may directly carry the lugs and the tensioning of the cutting wires can be effected in this manner with success.

It is also to be understood that changes, 40 variations and modifications may be made in the invention such as come properly within the scope of the claims hereunto appended

without departing from the spirit of the invention or sacrificing any of its advantages.

From the foregoing description, taken in 45 connection with the accompanying drawings, the construction and manner of operation of the herein described cutting machine will be readily apparent and, therefore, a more extended explanation has been 50 omitted.

Having thus described our invention, we claim:

1. A device of the kind described comprising a frame having extensions whereby 55 it may be supported over a receiving vessel, cutting wires strung on the frame in two sets, the wires of one set being at an angle to those of the other set, means for tensioning the said wires, an open top receptacle for butter or the like, the receptacle being mounted upon the frame, and a presser plate dimensioned to fit the said receptacle to extrude butter therefrom through the cutting wires, the receptacle being of a size to 60 65 serve as a container for the butter when removed from the frame.

2. A device of the kind described comprising a frame having extensions whereby it may be supported over a receiving vessel, 70 cutting wires strung on the frame in two sets, the wires of one set being at an angle to those of the other set, an open top receptacle for butter or the like, the receptacle 75 being mounted upon the frame, and a presser plate dimensioned to fit the said receptacle to extrude butter therefrom through the cutting wires, the receptacle being of a size to 80 serve as a container for the butter when removed from the frame.

In testimony whereof we affix our signatures.

JOHN F. McGINNITEY.
ROSS C. COX.
